Edmund Morse Pond Inventor
By his attorney A. V. Richardson

UNITED STATES PATENT OFFICE.

EDMUND MORSE POND, OF RUTLAND, VERMONT.

SURGICAL BANDAGE.

974,295.

Specification of Letters Patent.

Patented Nov. 1, 1910.

Application filed October 23, 1907. Serial No. 398,796. Renewed June 2, 1910. Serial No. 564,683.

To all whom it may concern:

Be it known that I, EDMUND MORSE POND, a citizen of the United States of America, and a resident of Rutland, county of Rutland, State of Vermont, have invented certain new and useful Improvements in Surgical Bandages, of which the following is a specification.

My invention relates to surgical bandages or medicated dressings for wounds, and has for its object the production of a bandage which will both hold the medicament in contact with the wound and permit the escape of the pus and other matter given off by the wound.

The best form of bandage at present known to me embodying my invention is illustrated in the accompanying drawing, in which:

20 Figure 1 is a face view of the bandage, and Fig. 2 is an exaggerated longitudinal section on line 2—2 of Fig. 1.

Throughout the drawing like reference figures indicate like parts.

25 1 is a sheet or layer of gelatin or similar substance capable of being gradually dissolved by the heat and moisture of the patient's body. This layer of gelatin is usually medicated and is of sufficient thickness to last for some time under the dissolving action of the warmth and moisture of the body with which it is placed in contact. This gelatin may also be mixed with some finely ground absorbent material such as 30 oakum, gauze, bran, etc.

35 2 is a sheet of oil silk or rubber tissue.

3 is a layer of gauze or other fibrous absorbent material. 4 another layer of material similar to 2.

40 5 is loose absorbent material usually of finer texture, and 6 is the containing layer of cloth or other fabric.

45 After the layers 1, 2 and 3 are assembled, the structure so formed is perforated to form cross sectional channels 7, 7. If desired, these holes 7, 7, may also extend through the layer 4.

50 In operation the heat and moisture of the wounds slowly dissolves the gelatin and constituents of layer 1. The dissolved materials and the excretions of the wound pass out through the holes 7, 7. The coarser substances so expelled are taken up by the layer 3 of gauze. The finer and liquid portions 55 pass on to the other layer 5 if the sheet 4 is perforated. The rubber or oil silk 2, pre-

vents the warm half melted gelatin from being absorbed by the adjacent absorbent material of layer 3, while the material dissolved on the inner face of layer 1, is freely 60 expelled through the holes 7, 7.

The advantages of my invention comprise its ability for freeing the face of the wound of excretions and the fluid gelatin mixed therewith, while a continuous supply of pure 65 medicated gelatin is maintained in contact with the wound, the complete absorption of the impure gelatin and secretions, and the preservation of the unused gelatin from premature absorption by the outer portions 70 of the bandage. The perforations in the layer 3 increase the area of its absorptive surface and so enable it to take up more rapidly the matter coming through the perforations in sheet 2. 75

Some of the outer layers of material shown and described could be omitted without losing all the advantages of my invention so long as the perforated layer of gelatin and the fluid-tight layer of material next 80 to it are retained with openings in line with the perforations in the gelatin.

While I have specified gelatin, other equivalent substances of a healing or non-irritating character, capable of solution in 85 water, or fusion at the normal temperature of the human body, such as cocoa butter or glycerin, might be substituted for the gelatin to produce the same result.

Having, therefore, described my invention, I claim:— 90

1. The herein described surgical bandage comprising a layer of gelatin, and a sheet formed of fluid-tight fabric having perforations extending through both gelatin and 95 backing sheet.

2. The herein described surgical bandage comprising a layer of gelatin, and a sheet formed of fluid-tight fabric having perforations extending through both, together with 100 a backing of absorbent material.

3. The herein described surgical bandage comprising a layer of gelatin, and a sheet formed of fluid-tight fabric having perforations extending through both, together with 105 a backing of absorbent material and a second sheet of fluid-tight material.

4. The herein described surgical bandage comprising a layer of gelatin, and a sheet formed of fluid-tight fabric having perforations extending through both, together with 110 a backing of absorbent material and a sec-

ond sheet of fluid tight material, the perforations also passing through the absorbent material.

5. The herein described surgical bandage comprising a layer of medicated gelatin, a sheet formed of fluid-tight material, a backing of coarse absorbent material, a second sheet formed of fluid-tight material and a second backing of finer absorbent material, 10 the gelatin, first fluid-tight sheet and first layer of backing having perforations in line one with the other extending through them.

6. The herein described surgical bandage comprising a layer of gelatin mixed with 15 finely ground absorbent material, and a sheet formed of fluid-tight fabric having perfora-

tions extending through both gelatin and backing sheet.

7. The herein described surgical bandage, comprising a thick layer of material soluble 20 in water at the normal temperature of the human body, and a backing formed of fluid-tight fabric provided with perforations, the soluble material having perforations extending through it in line with the perforations 25 in the fluid tight fabric.

Signed at Rutland, Vt., this 1st day of October 1907.

EDMUND MORSE POND.
